UNITED STATES PATENT OFFICE.

JACOB SPITZER, OF OAK PARK, ILLINOIS.

BLOOMERS.

Application filed May 1, 1922. Serial No. 557,698.

To all whom it may concern:

Be it known that I, JACOB SPITZER, citizen of the United States, residing at Oak Park, in the county of Cook and State of Illinois, have invented a certain new and useful Improvement in Bloomers, of which the following is a full, clear, concise, and exact description, reference being had to the accompanying drawings, forming a part 10 of this specification.

My invention relates to garments and more particularly to bloomers.

It is a purpose of the invention to provide a pair of bloomers with openings in the 15 sides thereof, to provide a drop seat portion, said openings dividing said bloomers into a front portion and a rear portion, said front portion being permanently attached to a belt, and the rear portion being 20 supported by said belt by being detachably secured to said front portion. Preferably the upper edge of said rear portion is provided with elastic to contract the same, and if desired the belt may be boned to form a 25 girdle.

Other objects and advantages of the invention will appear as the description of the accompanying drawings proceeds. However, I desire to have it distinctly understood that I do not intend to limit myself 30 to the exact details shown or described, but that I intend to include as part of my invention all such obvious changes and modifications of parts as would occur to a person 35 skilled in this art, and as would fall within the scope of the claims.

In the drawings:

Fig. 1 is a perspective view of my improved garment;

40 Fig. 2 is a view of the garment looking down at the same from the upper edge portion thereof;

Fig. 3 is a section thereof taken on the line 3-3 of Fig. 1;

45 Fig. 4 is a section taken on the line 4-4 of Fig. 1; and

Fig. 5 is a fragmentary side view of a portion of a modified form of belt.

Referring in detail to the drawings, the 50 improved bloomers comprise a body portion 10 which is provided with the leg portions 11 and which has openings or slits therein at 12 extending from the upper edge thereof down the sides of the garment over the 55 hips so as to provide a front section 13 and a back section 14. Secured to the upper

edge portion 15 of the front section 13 is a belt 16, said belt being secured thereto in any suitable manner as by means of stitches as shown at 17. The rear section 14 is free 60 of the belt 16, and said belt 16 is provided with hooks 18 and eyes 19 to secure the free end portion thereof together, said belt being made of such size as to properly fit the body of the wearer. 65

The rear section 14 is provided with a strip of elastic 20 arranged in a pocket 21 extending around the upper edge of said rear portion 14. Said elastic is made of such length as to tend to draw the rear section 70 together to a smaller size than the belt, thus placing the elastic under tension when the socket members 22 on the rear portion will engage with the stub members 23 on the front portion so as to close the garment 75 on the sides, said members 22 and 23 being of any suitable type of separable fastener.

It will be evident that due to the provision of the fasteners, the rear portion of the garment, when the fasteners 22 and 23 are 80 interengaged, will be supported by the belt 16 through the section 13 and that said belt will at all times that the hooks 18 and eyes 19 are engaged, support the forward portion 13, thus providing a drop seat garment. If desired, the belt instead of being made of ordinary non-elastic material 85 may be made as shown in Fig. 5, in which the belt 16' is shown as being provided with a plurality of stays 24 which are located 90 in the pockets 25 extending up and down in said belt 16', the belt in this form being more in the nature of a girdle.

Having thus described my invention, what I desire to claim and secure by U. S. Letters 95 Patent is:

1. A garment of the character described comprising leg portions, a body portion having openings at the sides thereof dividing said body portion into a front portion and 100 a back portion, a boned non-elastic belt substantially fitting the waist of the wearer secured to said front portion and means for securing said back portion to said front portion at said openings, said back portion being provided with elastic in the top thereof.

2. A garment of the character described, comprising leg portions, a body portion having openings at the sides thereof dividing said body portion into a front portion and 110 a rear portion, a non-elastic body encircling member secured along the top edge of said

front portion and extending from one free edge to the other free edge thereof for supporting said garment from the hips of the wearer, and means for securing said 5 rear portion to said front portion.

3. A garment of the character described, comprising a non-elastic body encircling member for closely engaging the body of the wearer, a body portion supported by said 10 member, said body portion having leg portions and having openings at the sides

thereof to divide said body portion into a front portion and a drop seat portion, said drop seat portion being free of said member between the free edges thereof, and an 15 elastic member engaging the top edge of said drop seat portion.

In witness whereof, I hereunto subscribe my name this 28th day of April, A. D. 1922.

JACOB SPITZER.
